DIAPER RINSER

Sherman G. Hodgson, Monroe, Wis.

Application March 1, 1956, Serial No. 568,740

5 Claims. (Cl. 4—1)

The invention relates to a moisture expressing device and more particularly to such a device for removing the water from diapers while suspended in a toilet bowl.

In the washing of soiled diapers it is common practice to use the toilet bowl as a wash basin, and after removing the soil, lift the cleaned diapers out of the bowl for rinsing. In removing a cleaned diaper from the bowl for rinsing there is always the chance of splattering water over the toilet floor, and this is objectionable. The main object of this invention is to provide a squeegee device adapted to be mounted on the rim of the toilet bowl in a position where it will not interfere with the normal use of the toilet, the device preferably being formed of a moldable resilient or yieldable plastic material.

A further object of the invention is to provide a squeegee device having a clampable base portion and squeegee blades projecting from said portion and arranged to have an open entrance end.

The invention further consists in the several features hereinafter described and more particularly defined by claims at the conclusion hereof.

In the drawings:

Fig. 1 is a perspective view of a device embodying the invention in its mounted position;

Fig. 2 is a plan view of the device;

Fig. 3 is a side elevation view of the device;

Fig. 4 is a front end elevation view of the device;

Fig. 5 is a detailed vertical sectional view taken on the line 5—5 of Fig. 3;

Fig. 6 is a perspective view showing certain modifications.

The device includes a base portion and a pair of squeegee blades projecting therefrom.

Referring to Figs. 1 to 5, the base portion 7 is of angled formation having an upper arm 8 adapted to extend over the top of the rim 9 of a toilet bowl 10 with a foot 11 engageable with the outer side of the rim and also carrying a rubber suction cup 12 engageable with the top side of the rim 9 though the suction cup may be omitted, if desired. Portion 7 also has a shorter arm 13 disposable below the lower side of the rim inside the bowl 10 and carrying a clamping screw 14, in a threaded opening therein, adapted to be screwed up against the lower side of the rim 9 so as to clamp said base portion 7 between said screw and the upper arm 8.

A pair of squeegee blades 15 are carried by the base portion 7 and extend into the bowl 10. Each blade 15 has a relatively heavy section 16 which is anchored at its rear end to the base 7 and a thinner section 17 which projects upwardly from the thicker section 16 and is free of the base. The blades 15 converge toward each other from their bottom sides to their top edges which are spaced apart to form a lengthwise extending entrance slot 18. The outer ends 19 of the blades 15 are preferably curved as indicated in Figs. 2 to 4.

In Figs. 1 and 3, the blades 15 are shown as inclining downwardly and inwardly from the base so as to limit the over all effective length that the blades project into the bowl so as not to interfere with the normal operation of the toilet. The blades 15 are sufficiently resilient so that when a diaper is pulled in from the lower ends of

2

blades into the slot 18 and then pulled up through this slot, the blades will give while exerting a yielding pressure on the diaper to extract the moisture therefrom.

In the modification shown in Fig. 6, the base portion 7A is similar in all respects to the base portion 7, but the blades 15A instead of projecting downwardly are laterally disposed relative to the base portion 7A. One of the blades 15A is anchored to said base portion, and the other blade 15A is connected to the rear end of the anchored blade by a connecting portion 20. The blades 15A are similar to the blades 15 having base portions of thicker cross sections than their upper portions, the anchorage to the base connecting with the thicker portion of one of the blades and the connecting portion 20 being connected to the thicker portion of the other blade so that the thinner portions of both blades 15A are free to flex outwardly. As in the first form, the flexible blades 15A converge toward each other to form an entrance slot 21 which extends to one of the ends of said blades so that when a diaper is pulled in from the open ends of the blades and up through the slot 21, the blades will exert a yielding pressure on the diaper to extract moisture therefrom. The lateral disposition of the blades reduces the over all area of the device that projects into the bowl so that it will not interfere with the normal operation of the toilet.

Both devices are preferably formed of a suitable resilient or yieldable plastic material that may be molded in one piece. However, it is possible to form the device 30 of fabricated metal parts or to suitably anchor metal blades to a plastic base portion so that the invention is not to be limited to the specific construction herein shown unless such limitations are included in the claims.

What I claim as my invention is:

35 1. In a device of the character described, the combination of an upstanding base provided with means for attaching it to the rim of a toilet bowl, a pair of yieldable squeegee blades carried by said base laterally thereof, said blades converging upwardly from their lower sides and spaced apart at their upper sides to form an entrance slot extending laterally from the base end of said device, said blades being positionable to allow moisture extracted by said blades to drain into said bowl and to remain in said bowl without interference with the normal functioning thereof.

40 2. In a device of the character described, the combination of an upstanding base provided with means for attaching it to the rim of a toilet bowl, a pair of yieldable squeegee blades carried by said base laterally thereof in a position below the upper side of the rim of said bowl and positioned to remain in said bowl without interference with the normal functioning thereof, said blades converging upwardly from their lower sides and spaced apart at their upper sides to form an entrance slot extending laterally from the base end of said device, each blade having a thin upper section and a lower section thicker than said upper section.

45 3. The device as defined in claim 1, wherein the blades are inclined downwardly and inwardly of said base.

50 4. The device as defined in claim 2, wherein the blades are inclined downwardly and inwardly of the base and have their thicker section portions anchored thereto at their back ends.

55 5. The device as defined in claim 1, wherein the blades extend parallel to a side of the base.
